UNITED STATES PATENT OFFICE.

WILLIAM A. MURRAY AND CHARLES E. PUTNAM, OF CHISHOLM, MAINE.

VALVE.

1,306,156.

Specification of Letters Patent. Patented June 10, 1919.

Application filed July 1, 1918. Serial No. 242,829.

To all whom it may concern:

Be it known that we, WILLIAM A. MURRAY and CHARLES E. PUTNAM, citizens of the United States, residing at Chisholm, in the county of Franklin and State of Maine, have invented certain new and useful Improvements in Valves, of which the following is a specification, reference being had to the accompanying drawings.

10 This invention relates to valves, and has for its primary object to provide an improved valve mechanism for automatically controlling the supply of pressure fluid to the opposite ends of a piston cylinder for 15 the reciprocating suction boxes of a Four-drinier paper making machine, such, for instance, as that shown in my pending application, Serial No. 234,544, filed May 13, 1918.

It is a more particular object of the invention to provide a valve mechanism which 20 will be instantaneous in its action, and is therefore particularly adapted for use in connection with pistons having a relatively short reciprocating stroke, said mechanism 25 including a pressure controlled cut-off valve operable to alternately admit the pressure fluid to the opposite ends of the piston cylinder.

It is also another detail object of our invention to provide improved means automatically actuated by the reciprocating piston, at the end of each stroke thereof, to effect the actuation of the cut-off valve by the pressure fluid and shift said valve to a position to admit the pressure fluid to the relatively opposite ends of the piston cylinder.

And it is also a further general object of the invention to provide a valve mechanism as above characterized, which will be 40 positive and reliable in its action, and which consists of relatively few, simply constructed parts, not liable to get out of order, and capable of manufacture at comparatively small cost.

45 With the above and other objects in view, the invention consists in the improved construction, combination and relative arrangement of the several parts as will be herein-after more fully described, subsequently 50 claimed and illustrated in the accompanying drawings in which similar reference characters designate corresponding parts throughout the several views, and wherein:—

Figure 1 is a vertical sectional view 55 through a piston and its cylinder, show-

ing the latter equipped with our improved valve;

Fig. 2 is a top plan view;

Fig. 3 is a section taken on the line 3—3 of Fig. 2;

Fig. 4 is a bottom plan view of the casting for the piston actuated valve;

Fig. 5 is a similar view of the fluid admission head; and

Fig. 6 is an end elevation of the piston 65 actuated valve.

Referring in detail to the drawings, 5 designates the body of the piston cylinder, to the opposite ends of which the heads 6 are securely fixed by means of the screws or 70 bolts 7. One of these heads is provided with a stuffing box for the piston rod 8, upon the end of which the piston 9 of any suitable construction is securely fixed to reciprocate within said cylinder. The body wall 5 of 75 the cylinder is provided, preferably at the top thereof and at its opposite ends, with the fluid inlet ports 10 and at the bottom of the cylinder and at each of its ends, pet cocks 11 are provided.

The piston 9 may be actuated by water, steam or other suitable pressure fluid, which is admitted to the cylinder through a supply head 12, which is securely fixed upon the top of the cylinder wall 5. This supply 85 head is formed with an elongated base portion 13 extending substantially the entire length of the cylinder, and above said base portion the head 12 is formed with a transverse bore 14, the opposite ends of which are 90 closed by means of suitable plugs 15. The pressure fluid is admitted to said bore through a passage 16 extending at right angles thereto and communicating with the bore at its center. The fluid is supplied to 95 said passage through a pipe, indicated at 17, suitably connected to the head 12 and extending from the supply source.

In the bottom face of the base portion 13 of the supply head, the non-communicating, 100 longitudinally extending channels 18 are formed, said channels at their inner ends being curved in relatively opposite directions and communicating with the transversely spaced ports or openings 19, formed 10 through said base portion of the supply head at the center thereof. These ports open into the bore 14 adjacent the opposite ends thereof. The supply head 12 is further formed with a passage 20 communicat- 11

ing with the upper side of the bore 14 at its center and opening upon the upper face of said head. Additional ports or openings 21 are formed through the supply head and 5 also open upon the upper face thereof, said ports communicating with the bore 14 at its opposite ends. A pressure controlled cut-off valve 22 is arranged in the bore 14 for free 10 sliding or reciprocating movement and controls the passage of the pressure fluid through the various ports or passages of the supply head, in a manner which will be hereinafter clearly explained. The intermediate portion of this cut-off valve is reduced in diameter to provide a continuous 15 annular, longitudinally extending chamber 23 within the bore 14.

Upon the supply head 12, a valve casing 24 is mounted, the axis of the valve casing 20 extending longitudinally of the piston cylinder. This casing is likewise formed with an elongated base 25 disposed transversely of the piston cylinder and suitably secured upon the upper surface of the head 12. An 25 opening 26, centrally formed through the base 25, is disposed in registering relation with the opening or passage 20 in the supply head, said opening 26 communicating with the bore of the valve casing. The base 30 plate 25 is likewise formed in its bottom face with the non-communicating, longitudinally extending passages 27, the inner ends of which are curved in relatively opposite directions and communicate with the trans- 35 versely spaced ports 28 extending through said base plate and communicating with the casing bore.

A cylindrical slide valve 29 is arranged in the casing 24, said valve having an axially extending bore 30 and the medial portion thereof being externally reduced in diameter to provide the annular chamber 31. A rod 32 is detachably threaded in one end of the bore 30 and extends through a suitable stuffing box 33 on one end of the valve casing 24. The other end of the valve casing is provided with a coupling nipple, indicated at 35, to which a waste outlet pipe 36 is adapted to be connected. At the end of the slide valve, to which the rod 32 is connected, the wall of said valve is provided with a plurality of spaced, obliquely inclined ducts 37, opening upon the end face of said valve and communicating with the bore thereof. These ducts permit of the free passage of the water or other pressure fluid through the bore 30 to the waste pipe in the movement of the valve in one direction and effectually overcome the possibility of a cushion being formed behind the valve member.

The upper end of an arm 38 is loosely engaged upon the valve rod 32, said rod at its lower end being securely fixed upon the piston rod 8. The upper end of the arm is movable upon the valve rod between

spaced collars 39, which are fixed upon said rod, these collars being adjusted and properly spaced from each other in accordance with the length of the piston stroke.

As will be noted from reference to Figs. 1 and 3 of the drawings, the outer ends of the respective passages 18 in the base 13 of the supply head, communicate with the cylinder ports or openings 10 at the opposite ends of the cylinder, while the outer ends of the passages 27 in the base plate of the valve casing 24 communicate with the respective ports or openings 21 in the supply head. Having now described the construction and arrangement of the various elements, the operation of our invention will be understood as follows:

Assuming that the parts are in the relative positions seen in Figs. 1 and 3 of the drawings, and the pressure fluid is being admitted through the supply head to the right hand end of the piston cylinder, said fluid acting against the piston drives the same to the opposite or left hand end of the cylinder. When the piston reaches the limit of its stroke in this direction, the arm 38 will engage the inner collar 39 on the rod 32 and thereby force the valve member 29 to the left so as to close the right hand port 28 and open communication between the left hand port 28 and the annular chamber 31 of the valve member. The pressure fluid flowing upwardly through the passages 20 and 26 will thus be admitted through one of the passages 27 to one end of the bore 14 and acting against the cut-off valve 22 will shift said valve so as to close the port 19 through which the pressure fluid is being admitted to the right hand end of the cylinder and open the other port 19, whereby the pressure fluid may flow from chamber 23 into the left hand end of the piston cylinder and acting against the piston reverse its reciprocating movement. When the piston reaches the limit of its movement in this direction, the arm 38 will strike the outer collar 39 and shift the slide valve 29 to the right, thereby again reversing the flow of the pressure fluid through the valve casing and the supply head 12. The fluid after having expended its force or pressure against the piston, finds an outlet through the pet cocks 11 when the movement of the piston is reversed. Thus, it will be seen that we have provided a very simple and at the same time positive and reliable valve mechanism which is automatically controlled in the reciprocating movements of the piston to alternately admit the pressure fluid to opposite ends of the piston cylinders. As this valve mechanism is very quick in its action, it will be appreciated that the device is particularly advantageous for use in connection with pistons having a relatively short reciprocating stroke. We have herein referred

to such a piston employed for actuating the suction boxes of a Fourdrinier machine, but it is of course manifest that the present invention is not limited in its utility to such 5 application, as it may likewise be adapted to use in connection with various other machines.

From the foregoing description, taken in connection with the accompanying drawings, the construction, manner of operation and several advantages of the invention will 10 be clearly and fully understood. The several parts of the device are compactly arranged and assembled upon the piston cylinder, and owing to the simple construction thereof will require but little care or attention upon the part of the operator. It will be understood, of course, that the relative 15 dimensions of the various elements and the fluid ports or passages will be determined in accordance with the dimensions of the piston cylinder and the pressure sustaining area of the piston, whereby the fluid in requisite volume will be admitted to the 20 ends of the cylinder.

While, therefore, we have shown and described what we have found to be one practical embodiment of our invention, it is to be understood that the device is susceptible 30 of considerable modification therein, and we accordingly reserve the privilege of adopting all such legitimate changes as may be fairly embodied within the spirit and scope of the invention as claimed.

35 We claim:—

1. In combination with a cylinder and piston reciprocating therein, means for alternately supplying a pressure fluid to the opposite ends of the cylinder including a slide 40 valve, a casing for said valve provided with an exhaust, said valve being provided with a bore in communication at opposite ends with the interior of the casing, and means carried by the piston to automatically actuate said valve at each end of the piston 45 stroke.

2. In combination with a cylinder and piston reciprocating therein, a pressure fluid supply head mounted upon the cylinder and 50 having ports for the admission of pressure fluid to the opposite ends of the cylinder, said head being further provided with a pressure fluid supply passage, a pressure actuated slide valve mounted in the head and

controlling the flow of the pressure fluid 55 from said passage to the respective ports, a valve casing secured upon the supply head, said head and the casing having communicating ports for the admission of the pressure fluid to the opposite ends of the slide 60 valve and being also provided with additional ports communicating with the supply passage, said casing being provided with an exhaust and a valve in said casing automatically actuated in the reciprocation of 65 the piston to admit the pressure fluid to the opposite ends of the slide valve and shift said valve to alternately supply the pressure fluid to the opposite ends of the cylinder, said last-named valve being provided with a 70 bore in communication at opposite ends with the interior of the casing.

3. In combination with a cylinder and piston reciprocating therein, a pressure fluid supply head mounted upon the cylinder and 75 having ports for the admission of pressure fluid to the opposite ends of the cylinder, said head being further provided with a pressure fluid supply passage, a pressure actuated slide valve mounted in the head and 80 controlling the flow of the pressure fluid from said passage to the respective ports, a valve casing secured upon the supply head, said head and the casing having communicating ports for the admission of the pressure fluid to the opposite ends of the slide 85 valve and being also provided with additional ports communicating with the supply passage, said casing being provided with an exhaust and a slide valve mounted in said 90 casing and automatically actuated in the reciprocation of the piston to direct the flow of the pressure fluid through the valve casing to the opposite ends of the first named slide valve, whereby the pressure fluid is 95 alternately supplied to the opposite ends of the piston cylinder, said last-named valve being provided with a bore in communication at opposite ends with the interior of the casing.

100 In testimony whereof we hereunto affix our signatures in the presence of two witnesses.
